CLAIM

The ornamental design for a vehicle wheel, as shown and described.

DESCRIPTION

FIG. 1 is a perspective view of a vehicle wheel showing my new design.

FIG. 2 is a front elevation view.

FIG. 3 is a rear elevation view; and,

FIG. 4 is side elevation view, the top, bottom, left, and right sides being a mirror image of one another.

The solid lines shown in the drawing depict portions of the vehicle wheel that form the claimed design. The stippled portions are for the purposes of clarification of the claimed design and are not a limiting feature of the claimed design. The broken lines shown in the drawings depict portions of the vehicle wheel that form no part of the claimed design.
